UNITED STATES PATENT OFFICE.

HENRY A. BROGNARD, OF PHILADELPHIA, PENNSYLVANIA.

GAS-BURNER.

SPECIFICATION forming part of Letters Patent No. 379,046, dated March 6, 1888.

Application filed March 29, 1887. Serial No. 232,875. (No model.)

To all whom it may concern:

Be it known that I, HENRY A. BROGNARD, a citizen of the United States, residing at Philadelphia, in the county of Philadelphia and 5 State of Pennsylvania, have invented certain new and useful Improvements in Gas-Burners; and I do hereby declare the following to be a full, clear, and exact description of the invention, such as will enable others skilled in the 10 art to which it appertains to make and use the same.

My invention relates to that class of lamps wherein the heat of the products of combustion from the flame is imparted to the air- 15 supply and to the combustible gas for increasing the illuminating power of the flame; and it consists in certain improvements in the construction of the regenerative gas-burner for which Letters Patent of the United States 20 have been granted to Charles M. Lungren on the 24th day of June, 1884. In these lamps, as heretofore constructed, the burner, which is screwed upon the lower end of the gas-supply pipe, consists of a chamber provided with 25 a number of tubes which project downward therefrom and terminate in a perforated annulus. These tubes are arranged at such a distance apart as to allow the air to circulate freely between them concentrically about a 30 rod which is provided at its lower end with a perforated deflector or button.

The object of my present improvement is to make the deflector and perforated dia- 35 phragm of the burner of one solid piece of metal, for the purpose of reducing the cost of manufacture and obviating the destructive ef- 40 fects of expansion and contraction arising from the extremes of heat and cold to which the parts are subjected.

45 In the accompanying drawings, Figure 1 is a vertical section illustrating the application of my improvement to a lamp of known construction. Fig. 2 is an enlarged view of the burner, partly in section; and Fig. 3 is a plan view of the same.

The burner, which is screwed upon the lower end of the gas-supply pipe E, consists of a chamber, D, provided with a number of tubes, d, which project downward therefrom 50 and terminate in a perforated annulus, d'. The tubes are arranged at such a distance apart as to allow the air to circulate freely between them concentrically about the rod H, which is provided at its lower end with a de- 55 flector-button, I. The tubes are surrounded

by a sheet-metal cylinder, A, which has its lower end turned outward in such a manner as to form an annular flange, a, which supports the outer edge of the diaphragm B. The part of the diaphragm B extending from 60 the outer edge of the perforations b to the outer edge of the flange a takes the place of the separate flame-plate which has heretofore been used, and thus the perforated diaphragm, which has been heretofore placed in the air- 65 passage between the burner-tubes and the cylinder surrounding them and the deflector, is formed of one and the same piece of metal.

In the lamp described in English Patent No. 14,335, of November, 1886, a thick cast- 70 iron flame plate or deflector is used in combination with a diaphragm; but it has been found that this construction is defective, because the thick cast-iron flame-plate absorbs a large 75 amount of heat, which absorption causes it to grow and become distorted, and also causes the disintegration of the washer to which it is attached and the overheating of the gas-tubes which it surrounds. It is also to be observed that in this lamp no provision is made for the 80 expansion and contraction occasioned by change of temperature, and the parts were therefore liable to become distorted and injured. These objections are obviated by making the perforated diaphragm and flame-plate 85 of the precise form required of a single piece of sheet metal having an annular recess for the reception of the annular projection or flange a upon the cylinder A and a cylindrical projection which rests loosely against the 90 ring d'.

Having thus described my invention, I claim and desire to secure by Letters Patent—

In a regenerative gas-burner, the combination of a perforated annulus, d', at the lower 95 end of the gas-tubes, a cylinder, A, provided with an annular flange, a, surrounding the burner, and a sheet-metal ring having its inner edge turned up to form a cylinder which slips loosely over the annulus d', and its outer 100 part bent downward and then upward to serve as a flame plate or deflector, and also to form an annular recess for the reception of the flange a.

In testimony whereof I have affixed my sig- 105 nature in presence of two witnesses.

HENRY A. BROGNARD.
